UNITED STATES PATENT OFFICE.

MAE R. WEDOO, OF GARNER, IOWA.

EMBROIDERY-HOOP.

1,199,952.

Specification of Letters Patent.

Patented Oct. 3, 1916.

Application filed March 11, 1916. Serial No. 83,655.

To all whom it may concern:

Be it known that I, MAE R. WEDOO, a citizen of the United States, residing at Garner, in the county of Hancock and State 5 of Iowa, have invented certain new and useful Improvements in Embroidery-Hoops, of which the following is a specification, reference being had to the accompanying drawings.

10 This invention relates to improvements in embroidery hoops, whereby a single set of hoops comprising an inner and outer hoop may be adjusted to various diameters and it is one object of the invention to provide 15 novel and efficient means for obtaining and positively retaining the hoops in an adjusted position.

Another object of the invention is to provide adjustable hoops in which a predetermined diameter may be readily and quickly obtained and in which a slight variation in the diameter of the hoops may be accomplished from their predetermined adjustments, whereby work of a heavy or light 25 grade material may be effectively clamped therebetween.

With the foregoing and other objects in view, the invention consists in the novel features of construction and arrangement 30 of parts as will be hereinafter more fully described, illustrated in the accompanying drawings and claimed.

In the drawings, Figure 1 is a perspective view of the outer hoop; Fig. 2 is a similar 35 view of the inner hoop; Fig. 3 is a sectional view through the assembled hoops.

Referring to the drawings by numerals, wherein is illustrated the preferred embodiment of my invention, 1 designates an elongated strip of flat, inherently resilient material which is adapted to be bent to provide a ring or hoop, as indicated in Fig. 1 of the drawings.

One end of the strip 1 has extending laterally from one longitudinal edge thereof, a relatively narrow strip 2 which is extended outwardly, as at 3, any suitable distance and then bent at right angles to itself to lie in spaced parallel relation to the outer face of 40 the strip 1 throughout its width and is then extended inwardly and secured to the strip 1, at its opposite longitudinal edge. In this manner a housing 4 is formed for a purpose which will presently appear.

45 Adjacent the housing 4 upon opposite longitudinal edges of the strip 1, are other

strips 5 which are of any suitable length and are bent to overlie a portion of the strip 1 and extend in spaced parallel relation thereto so as to receive and retain the free end of 60 the strip after it has been bent into hoop-shape and inserted between the strips 5, one of these strips being formed upon each longitudinal edge of the blank 1, as is illustrated to advantage in Fig. 1 of the drawing. Thus 65 the free end of the strip 1 is permitted of sliding movement relatively to the opposite end of the strip but is held against lateral displacement relative thereto. By adjusting the free end of the strip longitudinally 70 of the opposite end, the diameter of the hoop may be varied, as will be obvious.

At spaced intervals throughout the longitudinal extent of the free end of the strip 1 are arranged pairs of small openings 6, 75 while a thumb screw 7 is threaded through an opening 8 arranged centrally of the housing 4 to be engaged with any one of these openings to lock the hoop in any desired adjusted position. The threaded shank 9 of the 80 thumb nut 7 has secured thereto in any suitable manner, an element 10 such as a pin or washer to limit inward movement of the shank through the openings 6 and prevent accidental loss of the nut from the housing. 85

The hoop, as just described, is adapted to constitute the outer of a pair of hoops to make a complete embroidery holding device. The inner hoop is of substantially the same construction as the outer hoop, except 90 that the housing 4¹ is arranged interiorly, instead of exteriorly of the hoop and the free end of the strip 1¹ having the openings 6¹ therein is adapted to be slidably arranged between the flanges 5¹, which also extend inwardly from the opposite longitudinal edges of the inner hoop. By so constructing the 95 hoops, a smooth surface is provided upon the outer face of the inner and the inner face of the outer to receive the material A to be 100 embroidered. The thumb nut 7¹ threaded in the housing 4¹ in a manner similar to the thumb nut 7 is provided with a pin or washer 10¹ to limit its inward movement through the openings 6¹ and prevent its accidental 105 loss from the housing.

After the inner and outer hoops have been adjusted to a desired diameter, the material to be embroidered is placed over the inner 110 hoop in the ordinary manner, and the outer hoop then placed over the material to draw the same taut and to clamp the same between

the hoops. Where the material is of a heavy nature, the thumb nuts 7 and 7¹ may be disengaged from the openings 6 and 6¹ respectively and the hoops adjusted to slightly increase their diameters and the thumb nuts again engaged with the adjusted openings to lock the hoops in such adjusted position. Any desired number of openings may be provided in sets and these sets of openings 10 may be spaced apart any desired distance.

It will be obvious that minor changes in the form, proportion and arrangement of the parts of the hoops may be resorted to without departing from the spirit or sacrificing any of the advantages of the invention and, therefore, I do not wish to be limited to the details of construction herein shown and described, except for such limitations as the 15 claims may import.

20 I claim:—

1. An embroidery hoop including a strip 25 bent upon itself and having its ends overlapped, a housing formed on one end of the strip, the opposite end of the strip being provided with openings, a thumb nut thread- 30 ed in said housing for engagement with said openings, an element carried by the thumb screw to limit the inward movement of the same through the openings, and a second hoop in coöperation with said first hoop.

35 2. An embroidery hoop comprising a strip

of material bent upon itself and having its ends overlapped, a housing formed on one end of said strip and extending from its outer face, means carried by the housing for locking the opposite end of the strip in any longitudinally adjusted position, relatively to the first end of the strip, a second hoop 35 bent upon itself and having its ends overlapping, one end of said second hoop having a housing formed thereon, said housing being arranged upon the inner face of said second hoop, and means carried by said housing to lock the opposite end of the strip in any longitudinally adjusted position relatively to the opposite end of the strip. 40

3. An embroidery hoop including a flexible strip, a housing formed on one end of the strip, the opposite end of the strip being provided with openings, the opposite end 45 portions of the strip being adapted to overlap, a member adjustably mounted in said housing for engagement with the openings, and an element carried by the last-named member for limiting the inward movement 50 of the same through the openings.

In testimony whereof I hereunto affix my signature in the presence of two witnesses.

MAE R. WEDOO
